UNITED STATES PATENT OFFICE.

ANGUS R. MACDONALD, OF SYDNEY, NOVA SCOTIA, CANADA.

RAIL-BRACE.

1,101,463.

Specification of Letters Patent. Patented June 23, 1914.

Application filed April 2, 1914. Serial No. 829,077.

To all whom it may concern:

Be it known that I, ANGUS R. MACDONALD, a subject of the King of Great Britain, residing at Sydney, in the Province of Nova Scotia and Dominion of Canada, have invented certain new and useful Improvements in Rail-Braces; and I do hereby declare the following to be a full, clear, and exact description of the invention, such as will enable others skilled in the art to which it appertains to make and use the same.

This invention relates to new and useful improvements in rail braces, and has for its principal object to provide a combined rail brace and spike which will firmly hold a railroad rail in position on the tie, and prevent the same from becoming dislodged and from twisting during the passage of traffic over the road.

Another object of the invention is to provide a railroad spike which is capable of being used both as a spike and rail brace should it be so desired.

A further object of the invention is to provide a simple and effective rail brace which is capable of being used independently of the spike.

With these and other objects in view, the invention consists in the novel combination and arrangement of parts which will be fully set forth in the following specification and accompanying drawings, in which,

Figure 1 is a view of a railroad rail showing the same as it would appear when held in position on a tie by means of the spike and braces made in accordance with this invention, Fig. 2 is a side view of Fig. 1, and Fig. 3 is a transverse sectional view taken on line 3—3 of Fig. 1 and looking in the direction of the arrow.

Referring now to the drawings by characters of reference, the numeral 1 designates a railroad tie of the ordinary type to which the rail indicated generally by the numeral 2, is adapted to be secured. This rail 2 comprises the usual head 3, web 4, and flanges 5. The tie is provided with the usual tie plate 6 having formed therein the apertures 7 which are spaced from each other substantially the same distance of the width of the flanges 5 of the rail. Each of these apertures is so positioned as to receive the spikes which will be hereinafter described, so that the spikes will be in proper relation to firmly clamp the rail to the tie. A suitable notch 8 is formed in the upper surface of

the plate 6 and is arranged to receive the auxiliary rail brace 9 which is provided with the enlargement 10, in which the head 3 of the rail is adapted to seat when the device is in use.

The combined spike and braces, which are designated generally by the numeral 11, preferably comprise the two separate elements 12 and 13, which are arranged to co-operate with each other and are held in co-operating positions by means of the rectangular sleeve 14, by means of which the elements are removably held together. The element 12 preferably comprises the body portion 15, which is pointed as at 16 and is provided at its upper extremity with the enlarged head 17 having formed integral therewith at one extremity the upstanding projection 18. This upstanding projection 18 is provided with the beveled face 19 which is arranged to co-operate with the beveled face 20 formed on the co-operating brace member 13.

The brace plate, designated by the numeral 13, comprises the body portion 21, which is cut away at its lower extremity to form the beveled face 20 and which is curved at its upper extremity and cut away to form the head engaging piece 22 as clearly shown in Fig. 1.

It will be apparent from the foregoing that in use the spike formed of the element 12 is driven into the tie in the usual manner with the head portion 17 projecting over the flange of the rail. In this position it will be evident that the upstanding portion 18 of the spike member will be in the proper position to receive the co-operating member 13 which seats against the member 18 in such position that the seat 22 will engage the head of the rail and prevent the same from twisting. The sleeve 14 is then placed in the position illustrated in Fig. 2 so that the two elements are held firmly in place and it will be evident that a rigid and efficient rail brace is thereby provided. In the use of the auxiliary brace 9, it will be apparent that the portion 10 is brought into engagement with the head and the opposite end of the member 9 is seated within the notch 8, thus firmly holding the brace 9 in position.

While in the foregoing there has been shown and described the preferred embodiment of this invention, it is to be understood that such changes may be made in the

combination and arrangement of parts as will fall within the spirit and scope of the invention as defined in the appended claims.

Having thus described my invention, I

5 claim:

1. In a device of the character described, a rail brace comprising a spike, an upstanding portion formed on the spike, a brace member, a cut-away portion formed 10 on the brace member and adapted to form a seat for the head of a railroad rail when the device is in use, and a reduced extension at the lower extremity of the brace member and adapted to engage the upstanding portion 15 of the spike member to hold the brace member firmly in place and prevent the rail from becoming displaced.

2. In a device of the character described, a spike member, an extension formed on the 20 head of the spike member, a brace member, a cut-away portion formed at the upper extremity of the brace member to form a rail seat in which the head of the rail is adapted to rest when the device is in use, an extension formed at the lower end of the rail 25 brace member, and a sleeve surrounding the extension on the brace member and the ex-

tension on the spike member to hold the two elements firmly in place and prevent accidental displacement of the rail.

3. In a device of the character described, the combination with a railroad tie, a tie plate, and a railroad rail, resting on the tie plate, of a spike member extending through the tie plate, and overlying one of the flanges 35 of the rail, an extension on the spike member, said extension projecting upwardly toward the head of the rail, a brace member, a seat formed at the upper end of the brace member to receive the head of the rail to 40 prevent the same from tilting, an extension at the lower end of the brace member adapted to engage the extension on the spike member to prevent the lower end of the brace member from becoming displaced, and 45 a sleeve surrounding both extensions to firmly hold the whole together.

In testimony whereof I affix my signature in presence of two witnesses.

ANGUS R. MACDONALD.
